his Attorney

UNITED STATES PATENT OFFICE.

JOHN M. HESS, OF PHILADELPHIA, PENNSYLVANIA.

AIR-HEATING FURNACE.

SPECIFICATION forming part of Letters Patent No. 334,661, dated January 19, 1886.

Application filed November 14, 1884. Serial No. 147,971. (No model.)

To all whom it may concern:

Be it known that I, JOHN M. HESS, a citizen of the United States, residing in the city and county of Philadelphia, and State of Pennsylvania, have invented a new and useful Improvement in Air-Heating Furnaces, of which the following is a specification.

The object of my invention is to construct an air-heating furnace so that the warm air ¹⁰ may be more equally distributed to the heat-education pipes; and it consists in introducing a cold-air pipe into and up through the center of the main heating-cylinder, and arranging the upper end of the same so that the current ¹⁵ of pure cold air admitted from the outside of the building, after being warmed, is thoroughly distributed through the hot-air chamber.

Reference is had to the accompanying drawings, in which Figure 1 is a side elevation of ²⁰ my improvement in air-heating furnaces, with a portion of the inner and outer casing removed. Fig. 2 is a plan view on the line *a b* of Fig. 1. Fig. 3 is a vertical section through the heating chamber and cylinders. Fig. 4 is ²⁵ a plan view, detached, of the cold-air opening at the base of the furnace. Fig. 5 is a sectional view of the upper portion of the center or main heating-cylinder.

A, Figs. 1, 2, and 3, is the conical heating-³⁰ chamber placed in an inverted position on the cylinder or fire-pot B, and provided with a neck, *a*, which fits over and is secured to the annular projection on the upper end of the said fire-pot.

C ³⁵ is the main heating-cylinder, closed at the upper end and placed in a vertical position over an opening, *b*, made in the center of the conical heating-chamber A, as shown in Fig. 3.

C, C², C³, and C⁴ are a series of smaller ⁴⁰ heating-cylinders surrounding the main cylinder C, with their upper ends closed, and the lower ends opening into the conical heating-chamber A through the inclined pipes D, D', D², and D³. The said cylinders C', C², C³, and C⁴ are also connected near their upper ends ⁴⁵ by means of inclined pipes D⁴, D⁵, D⁶, and D⁷, for the passage of heat and smoke.

E, E', E², and E³, Figs. 1 and 2, are tubes leading vertically through the conical heating-⁵⁰ chamber, to allow air to pass through to be more thoroughly heated.

F, Fig. 3, is a cone-shaped heat-deflector,

suspended in each of the smaller heating-cylinders, to check the heat as much as possible from passing out the smoke-pipe.

G, Figs. 1, 2, and 3, is a cold-air pipe leading from the outside of the heater and up through the center of the main heating-cylinder C, and into the hot-air chamber H, for the purpose of admitting a current of pure ⁶⁰ air to be heated. The heating-cylinders are inclosed by the ordinary outer casing and inside lining of sheet-iron to form the hot-air chamber H, and also with a heat-dome provided with the usual heat-distributing pipes. ⁶⁵

In arranging the conical heating-chamber and cylinders, as described, an increased amount of heat-radiating surface is procured. The heat from the products of combustion passing from the fire-cylinder through the ⁷⁰ conical heating-chamber is radiated from the same to assist, in connection with the fire-cylinder, in heating the surrounding air of less temperature admitted through the opening I at the base.

The inclined pipes D, D', D², and D³, which connect the lower ends of the cylinders C', C², C³, and C⁴ with the heating-chamber A, may be of cast-iron, with the outer ends flared to suit the inside diameter of the cylinders. The ⁸⁰ object in placing these pipes, and also the pipes D⁴, D⁵, D⁶, and D⁷, at an incline is to avoid right-angle projections and flat surfaces, upon which dirt or soot is liable to collect.

To clean the cylinders, if necessary, a slight ⁸⁵ blow or rap upon the outside of each cylinder will dislodge any accumulation of dust or soot, and the inclination of the pipes and the inclined sides of the heating-chamber A will permit the refuse matter to pass freely down ⁹⁰ into the fire-chamber. The cap J, inclosing the upper end of the main heating-cylinder C, is depressed or dished in the center, and a conical plate, J', is secured a short distance above the same and over the open end of the ⁹⁵ pipe G, for the heat to impinge upon and scatter through the hot-air chamber.

K, Fig. 4, is a triangular partition placed opposite the cold-air entrance I at the base of the furnace, to cause the air to diverge to the ¹⁰⁰ right and left and pass thoroughly around the base of the fire-pot.

The smoke-pipe O, Fig. 1, is provided with a double elbow, P and P', provided with open

ends and adjustable caps or registers R and R', to check the draft when necessary, and also to ventilate the cellar.

I am aware that radiators and heat-domes have heretofore been in use, and that they have been arranged directly on the fire-pot, or connected with the same by means of pipes or flues, and that they have been made cylindrical and cone-shaped, and that cold air has been introduced and brought in contact with the radiators to be heated; hence I do not wish to broadly claim the use of radiators, heat or cold-air conducting pipes in connection with air-heating furnaces.

Having described my invention, what I claim, 15 and desire to secure by Letters Patent, is—

The combination of the fire-pot B, heating-cylinder C, provided with a dished end, J, air-pipe G, and conical plate J', to thoroughly diffuse the warm pure air issuing from the 20 upper end of the pipe G, substantially as shown and described.

JOHN M. HESS.
